UNITED STATES PATENT OFFICE.

LOUIS E. ENDSLEY, OF PITTSBURGH, PENNSYLVANIA, ASSIGNOR TO VERONA TOOL WORKS, OF PITTSBURGH, PENNSYLVANIA, A CORPORATION OF PENNSYLVANIA.

RAIL-JOINT SPRING.

Application filed September 13, 1927. Serial No. 219,272.

This invention relates to rail joint springs and is designed to provide an improved spring which bridges at least two bolts in the splice bar, and holds the splice bar with a yielding pressure so as to take up wear and reduce the battering of the rail ends.

In the Woodings Patent 1,416,152, dated May 16th, 1922, there is described and claimed a rail spring of the leaf type comprising a central portion having a curvature such that some degree of permanent set is obtained when the bolts are tightened.

While a rail spring of the Woodings type has been found generally satisfactory in operation, I have found that the exact degree of pressure which may be obtained from its use is somewhat uncertain, due to the permanent set which is effected when the rail spring is put in place. The Woodings rail spring initially engages the splice bar at a point substantially intermediate the bolts which engage it. I provide a rail joint spring whose central portion is adapted to initially engage the splice bar at spaced apart points. This central portion is preferably flat and the end portions are curved so as to lie away from the splice bar.

I preferably make the spring of varying thickness across its width. A desirable rail spring has been made channel-like in cross section with the thickened edges extending toward the splice bar. The bolt receiving holes are formed in the web portion of the channel. This cross section gives a greater section modulus than is secured in a rail spring of uniform thickness. It is found in practice that my improved spring can be compressed to a desired load with far less work than a spring of the Woodings type, and further, that a definite spring load can be secured.

In the accompanying drawings which illustrate the present preferred embodiment of the invention,

Figure 1 is a top plan view of a track joint having the invention applied thereto,

Figure 2 is a top plan view to enlarged scale of the rail spring,

Figure 3 is a side elevation thereof, and

Figure 4 is a section taken on the line IV—IV of Figure 2.

Figure 1 shows the meeting ends of track rails 2 connected by splice bars 3 and bolts 4. My improved rail spring is indicated gen-

erally by the reference character 5, and is shown as engaging pairs of bolts 4.

The rail spring is made of a metal bar whose cross sectional shape is shown in Figure 4. The bar has a flat central portion 6 adapted to initially lie alongside the splice plate 3. At each end the spring is provided with a portion 7 so curved that it lies initially out of engagement with the splice bar 3, but has its corners 8 directed toward the splice bar 3. Bolt holes 9 are provided in the curved portions 7. When the bolts 4 are drawn up, the corners 8 are pulled against the splice bar 3 and the central portion 6 is bowed slightly. This bowing is exaggerated in Fig. 1 for purpose of illustration. It is found in practice that no permanent deformation of the metal is effected and that a definite spring pressure can be secured for a given number of turns of the nuts 4a. It is also found that the desired spring pressure can be set up with fewer turns than in the case of a railway joint spring utilizing a permanent set.

While I have illustrated and described the preferred form of my invention, it will be understood that it is not thus limited, as the invention may be otherwise embodied within the scope of the following claims.

I claim:

1. A rail joint spring comprising a longitudinally curved bar, the bar material being of varying thickness across its width.

2. A rail joint spring comprising a longitudinally curved bar, the bar being channel-like in cross section.

3. A rail joint spring comprising a longitudinally curved bar, the bar having a thin central portion with a thickened edge.

4. A rail joint spring comprising a longitudinally curved bar, the bar having a recess formed in a face thereof so as to provide a spring of varying thickness across its width, the recess lying on the side of the rail spring which is adjacent the rail in use.

5. A rail joint spring comprising a bar having a central portion adapted to initially engage a splice bar at longitudinally spaced points, and curved portions lying at either end of the space defined by such points, the curved portions having openings there-through to receive bolts.

6. A rail joint spring comprising a bar having a central portion adapted to initially

engage a splice bar at longitudinally spaced points, and curved portions lying at either end of the space defined by such points, the free ends of the curved portions initially 5 lying clear of the splice plate, the curved portions having openings therethrough to receive bolts.

7. A rail joint spring comprising a bar having a central flat portion adapted to lie 10 along a splice bar, and having curved portions lying at either end of the flat portion, the curved portions having openings therethrough to receive bolts.

8. A rail joint spring comprising a bar of 15 varying thickness across its width, the bar having a central portion adapted to initially engage a splice bar at longitudinally spaced points, and having curved portions lying at either end of the space defined by such points, 20 the curved portions having openings therethrough to receive bolts.

9. A rail joint spring comprising a bar of 25 varying thickness across its width, the bar having a central portion adapted to initially engage a splice bar at spaced points, and having curved portions lying at either end of the space defined by such points, the curved portions have openings therethrough to receive bolts, the bolt holes being in a thinner 30 portion of the material.

10. A railway joint spring comprising a bar of varying thickness across its width and channel-like in cross section, the bar having a central portion adapted to initially engage 35 a splice bar at longitudinally spaced points, and having curved portions lying at either end of the space defined by such points, the curved portions having openings therethrough to receive bolts, the bolt openings being formed in the web of the channel.

11. A rail joint spring comprising a bar having a central flat portion adapted to initially lie alongside the splice plate, and having curved end portions so shaped as to be 45 convexed outwardly, the free ends of the curved portions initially lying clear of the

splice plate, such curved portions having openings therethrough to receive bolts.

12. A rail joint spring comprising a bar having a central portion adapted to initially 50 engage a splice bar at longitudinally spaced points, and having end portions, the end portions being bent outwardly from the central portion and then curved so as to present a convex outer face, the curved portions having 55 openings therethrough to receive bolts.

13. A rail joint spring comprising a bar having a central portion adapted to initially 60 engage a splice bar at longitudinally spaced points, and having end portions, the end portions being bent outwardly from the central portion and then curved so as to present a convex outer face, the free ends of the curved portions initially lying clear of the splice plate, the curved portions having openings 65 therethrough to receive bolts.

14. A rail joint spring comprising a bar having a central portion adapted to initially engage a splice bar at longitudinally spaced 70 points, the end portions of the bar extending first outwardly and then inwardly so as to form curved portions whose free ends will engage the splice bar, the curved portions having openings therethrough to receive bolts.

15. A rail joint spring comprising a longitudinally curved bar, the bar being channel-like in cross section, having a relatively thin central web and relatively thicker edges, and having a convex outer face.

16. A rail joint spring comprising a longitudinally curved bar, the cross section of the bar remaining substantially constant throughout its length, the bar material being of varying thickness across its width.

17. A rail joint spring comprising a longitudinally curved bar of substantially uniform cross section, the bar material being of varying thickness across its width.

In testimony whereof I have hereunto set my hand.

LOUIS E. ENDSLEY.
